US0D1079024S

(12) United States Design Patent (10) Patent No.: US D1,079,024 S
(45) Date of Patent: * Jun. 10, 2025

(54) THERAPEUTIC BELT

- (71) Applicant: ZheJiang E-cozy Electronic Technology Co., Ltd., Zhejiang Province (CN)
- (72) Inventors: Shousheng Tang, Zhejiang Province (CN); Daojin Tang, Zhejiang Province (CN); Jianshou Chen, Zhejiang Province (CN)
- (73) Assignee: ZheJiang E-cozy Electronic Technology Co., Ltd., Zhejiang Province (CN)
- () Term: 15 Years
- (21) Appl. No.: 29/881,790
- (22) Filed: Jan. 6, 2023

(30) Foreign Application Priority Data

- Sep. 14, 2022 (CN) 202230605335.1
- (51) LOC (15) Cl. 24-02
- (52) U.S. Cl.
USPC D24/188
- (58) Field of Classification Search

CLAIM

The ornamental design for a therapeutic belt, as shown and described.

DESCRIPTION

FIG. 1 is a front perspective view of the therapeutic belt showing our new design;

FIG. 2 is a back bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom thereof.

The broken lines shown in the design depict a strap that is for illustrative purposes only and forms no part of the claimed design.

1 Claim, 8 Drawing Sheets
